UNITED STATES PATENT OFFICE.

ARTHUR FREDERICK EWART, OF HONOLULU, TERRITORY OF HAWAII, ASSIGNOR TO
HONOLULU IRON WORKS COMPANY, OF HONOLULU, TERRITORY OF HAWAII, A
CORPORATION OF THE TERRITORY OF HAWAII.

INTERMEDIATE CONVEYER FOR SUGAR-CANE MILLS.

1,169,946.

Specification of Letters Patent.

Patented Feb. 1, 1916.

Application filed February 27, 1915. Serial No. 10,951.

To all whom it may concern:

Be it known that I, ARTHUR FREDERICK EWART, a subject of the King of Great Britain, and a resident of the city and county of Honolulu and Territory of Hawaii, have invented certain new and useful Improvements in Intermediate Conveyers for Sugar-Cane Mills; and I do hereby declare the following to be a full, clear, and exact description of the invention, such as will enable others skilled in the art to which it appertains to make and use the same.

This invention relates to improvements in intermediate conveyers employed between sugar-cane mills for moving the crushed cane or bagasse discharged from one mill and feeding it to the succeeding mill.

The present invention is in the nature of improvements on the removable intermediate conveyer described in my application for United States Letters Patent filed Oct. 21, 1914, as Serial No. 867,890.

While retaining some of the salient features therein described, the object of the present invention is to provide an arrangement of such a conveyer whereby its removable trough will be approximately level, in order that the means for aiding the movement of the blanket of bagasse through the trough will also act as a force feeder.

Another object is to arrange said means for aiding the movement of the blanket so that the said means will be floating and automatically accommodate itself to the various thicknesses of the blanket of bagasse passing through the trough.

With these and other objects in view, as will hereinafter more fully appear, the invention consists in the novel combination and arrangement of parts as hereinafter described and claimed, reference being had to the accompanying drawings, forming a part of this specification, in which—

Figure 1 represents a sectional elevation approximately through the middle longitudinally of an intermediate conveyer embodying my improvements. Fig. 2 is a side elevation of the same conveyer when detached from the mills. Fig. 3 is a plan view showing, diagrammatically the shafts and the driving arrangement of the same conveyer.

Referring to the drawings, the bagasse

discharged from the three-roller sugar-cane mill A is to be conveyed and fed to the succeeding mill B. The trough C between the mills A and B is removable, preferably water tight, and substantially horizontal. The trough C is composed of the bottom plate 5 secured to the angles 6 and 7 riveted to the inside of the side plates 8 and 9 above their lower edges respectively. The angles 10 are attached to the upper edges of the side plates 8 and 9 transversely of the trough C, to form separators. The short piece of angle 11 secured to each of the side plates 8 and 9 is adapted to rest on a similar angle 12 attached to each of the cheeks of the mill A. The angles 13 secured to the side plates 8 and 9, near the rear end of the trough C, are adapted to rest directly on the inclined portion of the cheeks of the mill B. The rear ends of the side plates 8 and 9 are bolted by the bolts 14 to the feed side plates 15 of the mill B.

The shaft 16 is journaled in the boxes 17 adapted to slide vertically in the frames 18 secured to the side plates 8 and 9 respectively rearward of the angles 11. The shaft 16 passes through a hole 19 in each of the said side plates. The springs 20 normally hold the boxes 17 in their lowest position in the frames 18. The shaft 21 is journaled in the boxes 22 which are adjustably attached to the rear ends of the bars 23. The forward ends of the bars 23 are provided with eyes 23^a which surround the shaft 16, so that said bars may swing on the shaft 16 as a pivot. The sprockets 24 and 25 are secured to the shafts 16 and 21 respectively, over which the endless chains or link belts 26 are passed. The angles 27 are secured at intervals to these strands of link belts 26 transversely of the trough C, so that the angles 27 attached to the lower strands of the belts 26 are adapted to engage the blanket of bagasse in the trough C.

The shaft 28 is journaled in the boxes 29 adapted to slide in the frames 30 secured to the side plates 8 and 9 respectively, said shaft passing through holes in the side plates. The shaft 28 is also journaled in the boxes 31 attached to the bars 23, and is provided with the sprockets 32 and 33. The upper strands of the link belts 26 engage the sprockets 32.

The driving sprocket 34 is keyed to the

top shaft of the mill B. The short shaft 35, provided with the sprockets 36 and 37, is journaled in the boxes 38 attached to the cheek of the mill B. The link belts 39 and 40 connect the sprockets 34 with 36 and 33 with 37 respectively. The sprocket 34 in revolving with the top roll of mill B thus revolves the shaft 35, which in turn revolves the shaft 28, causing the link belts 26 with the angles 27 attached thereto to travel in the direction as indicated by arrows, Fig. 1, and at the same speed as that of the periphery of the discharge roll of mill A.

10 Idler pulleys 41 secured to the shaft 42 journalized in the boxes 43 attached to the bars 23 may be employed to depress the lower strands of the belts 26.

15 The lower scraper plate 44 of mill A is secured to the scraper bar 45 adapted to turn 20 in the brackets 46 attached to the side plates 8 and 9 respectively. The toe of the scraper plate 44 engages the discharge roll of mill A, the pressure being applied by the levers 47 and turnbuckles 48 in the usual manner.

25 The rear edge of the scraper plate 44 overlaps the forward end of the bottom plate 5 of the trough C.

30 Maceration liquid may be applied to the bagasse discharged from the mill A by means of the pipes 49 and 50 which are provided with holes above the forward end of the trough C. Maceration may also be applied underneath the blanket of bagasse, while passing over the forward end of the 35 bottom plate 5, through the pipe 51, screwed into the casting 52 attached to the under side of said plate, and through holes 53 in said plate above the channel 52^a in said casting.

40 In operation, the crushed cane or bagasse discharged from the mill A is pushed rearward over the lower scraper plate 41 into the trough C, whereupon the flights 27, moving at the same speed as that of the blanket 45 of bagasse discharged from mill A, engage this layer or blanket of bagasse and aid its movement along through said trough and force the blanket between the top and feed rollers of mill B. The arrangement of

50 means for aiding or propelling the blanket of bagasse through the trough C is such that it automatically accommodates itself to the

varying thicknesses of the blanket, for the forward end has a vertical movement, the boxes 17 sliding in the frames 18 against the action of the springs 20, and the rear end has a swinging movement, the bars 23 turning on the shaft 16 as a pivot. The depressing of the lower strands of the belts 26, by the rollers 41 on the idler shaft 42, also permits the flights 27 to more gradually be withdrawn and leave the blanket of bagasse in passing around the sprockets 25. In the event of the mill B not taking the feed of the blanket as rapidly as the blanket is moved in the trough C, thus causing the bagasse to be retarded in the trough C in front of said mill, the propelling or aiding means is automatically lifted by the accumulating bagasse, the same swinging on the shaft 16 as a pivot.

55 70 Maceration may be applied both above and below the blanket of bagasse as discharged from the mill A, as previously described. As the trough C is made water tight, the leakage of juice or of maceration liquid is 75 prevented.

75 By disconnecting the driving link belt 40, the maceration pipes 49 50 and 51, and the turnbuckles 48 from the levers 47, and by removing the bolts 14, the conveyer is detached from the mills A and B and may then be easily lifted and removed, for example, by means of ropes attached to the angle separators 10.

80 I claim:

85 An intermediate carrier for sugar-cane mills, comprising a trough adapted to support the bagasse, and an endless conveyer associated with said trough, one run of which is adapted to engage the top of the blanket 90 of bagasse to force the feed toward the rearward mill, one end of said conveyer being mounted for substantially vertical raising and lowering movements and the other end thereof being mounted for movements in an 95 arc of a circle about the first-named end as a center.

95 In testimony whereof I affix my signature, in presence of two witnesses.

ARTHUR FREDERICK EWART.
